UNITED STATES PATENT OFFICE.

FANNIE B. FONDILLER, OF NEW YORK, N. Y.

WINDOW PORCH.

1,402,410.

Specification of Letters Patent.

Patented Jan. 3, 1922.

Application filed June 15, 1920. Serial No. 389,120.

To all whom it may concern:

Be it known that FANNIE B. FONDILLER, a citizen of the United States, and resident of the city of New York, in the county of New York and State of New York, has invented certain new and useful Improvements in Window Porches, of which the following is a specification.

This invention relates to window porches or balconies.

One of the objects thereof is to provide a device of this type which shall be portable and adapted to be attached outside of any window frame from within.

Another object of this invention is to provide a strongly made balcony which can be readily and compactly collapsed for transportation and which can be easily set up in place outside of the window without requiring much skill or experience.

A further object is to provide a device of the above type which shall be neat in appearance, safe in operation and cheap and simple in construction.

A still further object of this invention is to provide a device of this type which may be adjustable for varying widths of window.

Other objects of this invention will be in part obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawings, in which is shown one of various possible illustrative embodiments of this invention,

Fig. 1 is a front elevation of a window balcony embodying this invention;

Fig. 2 is a bottom plan view thereof;

Fig. 3 is a side elevation looking in the direction of line 3—3 of Fig. 1 and shown in position outside the window frame; and

Figs. 4 and 5 are detailed cross-sectional views taken respectively along lines 4—4 and 5—5 of Fig. 1 and show the means used in jointing the members of the device to each other.

Referring in detail to the drawing, the window porch or balcony embodying the

invention there shown is seen to comprise two front members 1 and 2, bottom or floor members 4 hinged to the front members as at 3 and side members 5 hinged to the ends of the front members as at 6. The front members 1 and 2 comprise each a frame 7, 7' preferably rectangular and a wire net-work filling 8 held to the frame by suitable means such as the holding straps 9, 9' as will be clear from the drawing. The top and bottom members 10, 10, of the frame 7 of front member 1 are preferably tubular 65 and the side of said frame is bent at the ends thereof to rigidly fit into one end of the tube as shown at 10^a, 10^a, while the other end of the tube receives telescopically the top and bottom pieces of the frame 7' of the front member 2 as shown at 10^b. In this way the balcony may be made adjustable to various widths of windows, the frame 7' being slidable in the members 10. The holding straps 9' are formed with extensions 9^a 75 the ends of which are bent at right angles 9^b and the frame 7' carries a cross member 7^a so that when the balcony is extended to its maximum width the front members 1 and 2 meet and abut against each other as shown 80 in Fig. 4, thus preventing the two sections from coming apart as will be clear from said figure and Fig. 1.

The bottom and side members 4, 5 are similar in construction to the front member 85 and comprise a frame 11 and 12 respectively, and similar wire net-work 8. Top members 13 and 14 similar to the bottom members 4 may be hinged to the front members 1 and 2 as at 15 if desired, in order to 90 provide a screen or guard to prevent objects from dropping into the balcony and endangering the occupant thereof. To secure the balcony to the outside window frame the side members 5 are provided at 95 their rear ends with attaching plates 16 having bayonet slots 17 adapted to receive the screws or bolts 18 whereby the balcony may be secured from the inside to the window frame 19 with the bottom members resting on the window sill 20 (Fig. 3). The means for securing the members to each other in such a way as to provide a collapsible construction foldable into compact form for transportation will now be described.

Referring now to Fig. 5, the hinged mem-

bers 3 are preferably formed from a strip of heavy sheet metal 21 curved at the ends to form cylindrical members 22 and 23 adapted to receive respectively the bottom 5 member 10 of the frame 7 of the front member and the forward end 25 of the frame 11 of the bottom members. The hinges 6 and 15 may be of similar or like construction, and when the members are swung about the 10 hinges so as to be fully extended, they form a rigid balcony that will not collapse while in place, so that no danger may attach to its use, and the device when set in place as herein described may thus serve as a safe 15 support for a person cleaning the outside of the window or as a fresh air space for a child.

To fold the device for shipment the side members 5 are first raised so as to unhook 20 them from the bolts, the top member is folded over against the front members on the hinges 15 while the side members 5 are folded inward against the interior side of the front members on the hinges 6 while 25 the bottom members are folded up against the front members on the hinges 3, thus resulting in a flat, compact article for shipment.

It will thus be seen that there is provided 30 apparatus in which the several objects of this invention are achieved and which is well adapted to meet the most severe conditions of practical use.

As various possible embodiments might be 35 made of the above invention and as various changes might be made in the embodiment above set forth, it is to be understood that all matter herein set forth or shown in the accompanying drawings is to be interpreted 40 as illustrative and not in a limiting sense.

Having thus described my invention, I claim as new and desire to secure by Letters Patent:—

1. A window porch adjustable to the 45 width of a window comprising an adjustable front section, side sections, a top section, a bottom section, each of said sections comprising a frame, wire netting, and means for securing said netting to said 50 frame, and sheet metal clasps for foldably connecting adjacent sections together.

2. In a window porch comprised of sections suitably secured to each other, a 55 screened section comprising a frame, wire netting, cut away straps bent around said frame and clenched to said netting for securing said netting to said frame, and hinges of a single piece of sheet metal in the cutaway part of said straps and bent 60 around said frame for foldably securing said section to an adjacent section.

3. In a window porch comprised of sections suitably secured to each other, a screen 65 section comprising a frame, wire netting, straps bent around said frame and clenched

to said netting, hinges rotatably connecting said sections for allowing said sections to be folded together, and means for removably supporting said porch in a window opening comprising apertured plates secured to a section and bolts in said window opening adapted to engage said plates. 70

4. A window porch adjustable to the width of a window opening comprising an adjustable front section, side sections, a top section, a bottom section, each of said sections comprising a frame, wire netting and cut-away straps bent around said frame and clenched to said netting for securing said netting to said frame, hinges for foldably 75 securing said sections to each other arranged in the cutaway part of said straps, and means attached to the side sections for removably supporting said porch in said window opening. 80

5. In a window porch, an adjustable front section comprising a frame, tubular horizontal members in said frame, a vertical member in said frame, horizontally disposed extensions bent from said vertical member 90 and secured in said tubular members, wire netting, straps securing said netting to said frame members, horizontal extensions of the straps of said tubular members, a vertically disposed member connecting said extensions, 95 bent at right angles to the plane of said netting, a second frame adjustable relatively to said first frame, horizontally disposed members in said second frame arranged to slide into said tubular members, netting in said second frame, a vertically disposed member at the inner edge of said second frame, bent substantially at right angles to said netting and adapted to engage the vertical connecting member of said first frame 100 for limiting the relative movement of said frames. 105

6. In a window porch, an adjustable front section comprising a frame, tubular horizontal members in said frame, wire netting, 110 means for securing said netting in said frame, a second frame, horizontally disposed members in said second frame adapted to enter said tubular members, wire netting in said second frame, means for securing said netting in said second frame, and extensions at the inner edges of said frames for limiting the relative movement of said frames, side sections, wire netting in said side sections, a top and a bottom section similar 115 to said front section, and hinges, each of a single piece of sheet metal rotatably connecting said sections for allowing said sections to be folded together. 120

7. In a window porch, adjustable front, 125 bottom and top sections, each comprising a frame, tubular members in said frame, netting secured to said frame, a second frame, members in said second frame arranged to enter the tubular members of the first men- 130

tioned frame, netting in said second frame, and means on said frames for limiting the relative movement of said frames, side sections, netting in said side sections, means for foldably connecting said sections, and means for removably supporting said porch in a window opening comprising apertured plates secured to said side sections, and bolts

in the walls of said window opening adapted to engage said plates.

Signed at New York city, in the county of New York and State of New York this 12th day of June A. D. 1920.

FANNIE B. FONDILLER.

Witness:

WILLIAM FONDILLER.
